UNITED STATES PATENT OFFICE.

FRANK SCHEIER, OF CLEVELAND, OHIO, ASSIGNOR OF ONE-HALF TO JOSEPH PFAFF, OF CLEVELAND, OHIO.

FLUSHING-TANK.

1,335,715.

Specification of Letters Patent. Patented Mar. 30, 1920.

Application filed January 29, 1919. Serial No. 273,853.

To all whom it may concern:

Be it known that I, FRANK SCHEIER, citizen of the United States, residing at Cleveland, in the county of Cuyahoga and State 5 of Ohio, have invented certain new and useful Improvements in Flushing-Tanks, of which the following is a specification.

My invention relates to an improvement in flushing tanks and the object of the invention is to provide a flexible or bendable siphon for the tank adapted to empty the contents of the tank at the will or election of the operator. This device eliminates the need of a valve at the flushing outlet, together with all the known troubles incident to the use of such valves, especially the rubber bulbs more commonly used.

In the accompanying drawings, Figure 1 is a side elevation and vertical section of the 20 flushing tank embodying my invention, and Fig. 2 is a plan view and horizontal section of Fig. 1.

The tank 2 may be of any suitable construction adapted to hold a predetermined 25 amount of water, the level or height of which is fixed by a valve 3 and float 4. This valve is mounted to slide upon the upper end of a supply pipe 5 which extends upwardly into the bottom of the tank, and the 30 float 4 is pivotally mounted at the upper end of a screw-threaded stem 6 carried by a lug 7 on the supply pipe. Adjustment of the screw stem to raise or lower the pivot for the float determines the level of the water in the 35 tank, and this level is fixed at a slight distance below the bend 8 in an inverted U-shaped siphon member 9 having a flexible or bendable portion 10, shown in Fig. 1 as a separate rubber tube or pipe reinforced or 40 strengthened internally by a coiled spring 11. The intake end 12 of this siphon member may be of metal with its extremity 13 bent to project substantially parallel with the vertical extension of the outlet pipe 14 which is secured to or made integral with 45 an outlet fitting or member 15 fastened by a nut 16 at the bottom of the tank. The intake and bendable portions of the siphon member are preferably inclined or set at an angle to promote an instant flow and 50 complete submersion of the upper bend 8 upon imparting a pull or push thereto through the medium of an operating device of any suitable character. As shown, a lever 18 is used

which is operated by a handle 19 placed 55 upon the outside of the tank and when the siphon member is flexed and carried beneath the level of the water, a flow of water is established through the siphon member and the tank siphoned of its contents. As 60 soon as the water level drops to the open extremity 13 and air is admitted the siphoning action is broken and cannot be again established unless water is again admitted into the tank and maintained at the original 65 higher level.

Admission of water into the tank is automatically controlled by valve 3 and float 4. Thus, when the float drops valve 3 is raised sufficiently from the upper end of supply 70 pipe 5 to admit water into the tank through the lateral passage 20 and a downwardly-extending pipe 21, and the inflow of water into the tank will continue until the float 4 rises and sets valve 3 solidly against the 75 upper end of supply pipe 5.

A by-pass pipe 22 is also provided to deliver water from the supply pipe 3 directly to a branch stand-pipe 23 which connects with the outlet fitting 15 for the tank, but 80 the flow through this by-pass 2 is shut off when the tank is full and valve 3 is seated and closed. The purpose of this auxiliary flow of water to the outlet for the tank is to supply the closet bowl with sufficient water 85 to fill the bowl to a predetermined level after flushing operations.

What I claim is:

1. In flushing tanks, a tank and an outlet fitting extending into the tank and bent 90 laterally at its inner end, a flexible tube affixed to said fitting and projected in continuation of the bend therein, a coiled wire spring engaged with the walls of said tube and adapted to sustain the same in normal 95 position, a siphon tube having a U-shaped extremity secured to the upper end of said flexible tube and provided with a straight body portion lying relatively over the back of said flexible tube and parallel therewith and having its intake end bent inwardly 100 toward the said outlet fitting and the mouth thereof relatively near the bottom of the tank, and means to bring said tubes into siphon starting position.

2. In flushing tanks, a rigid fitting in the bottom of the tank having a laterally curved end, a straight rubber tube secured to said

end and a sustaining spring coil therewith, a siphoning tube having one end bent to U-shape and fixed upon said rubber tube and said siphoning tube having a straight body disposed lengthwise over and next to the said rubber tube and having its lower end partially overlapping said rubber tube and bent inward parallel thereto.

3. In flushing tanks, a tank having a tubular fitting set upright in the bottom thereof and having its inner end turned to an inclined position, a straight flexible tube pro-

jecting in prolongation of said bent end and secured thereto and a coiled wire spring in said flexible tube adapted to sustain the tube 15 in working position, a siphoning tube having a U-shaped end fixed on said flexible tube and having its body inclined and its intake end bent toward said fitting, and means to actuate said tubes and cause them to siphon. 20

Signed at Cleveland, in the county of Cuyahoga, and State of Ohio, this 8th day of January, 1919.

FRANK SCHEIER.
